Primary Examiner — Robin V Webster(74) *Attorney, Agent, or Firm* — Ohlant, Greeley, Ruggiero & Perle, LLP(57) **CLAIM**

The ornamental design for the water purification media device, as shown and described.

DESCRIPTION

FIG. 1 is a top perspective view of the water purification media device according to the present disclosure;

FIG. 2 is a first side view of the water purification media device of FIG. 1, the opposite sides being a mirror image thereof;

FIG. 3 is a second side view of the water purification media device of FIG. 1, taken ninety degrees from the view of FIG. 2, the opposite sides being a mirror image thereof;

FIG. 4 is a top view of the water purification media device of FIG. 1; and,

FIG. 5 is a bottom view of the water purification media device of FIG. 1.
